UNITED STATES PATENT OFFICE.

JAMES SCOTT, OF DENVER, COLORADO.

DESIGN FOR A DIAL.

SPECIFICATION forming part of Design No. 15,448, dated October 7, 1884.

Application filed February 27, 1884. Term of patent 14 years.

To all whom it may concern:

Be it known that I, JAMES SCOTT, a citizen of the United States, residing at Denver, in the county of Arapahoe and State of Colorado, ⁵ have invented a new and useful Design for the Dials of Clocks, Watches, &c., of which the following is a specification, reference being had to the accompanying drawing.

This invention relates to a design for the ¹⁰ dials of clocks, watches, and other time-pieces; and it has for its object to provide a new, attractive, and ornamental dial, as hereinafter set forth, and particularly pointed out in the claim.

¹⁵ In the accompanying drawing the single figure illustrates a plan view of a dial.

Referring to the drawing, A designates an ordinary dial of a clock, watch, or other time-piece, constructed in the usual manner with ²⁰ an inclosed space, B, surrounded by two circles, C C'. Within the space B are two series of small circles, twelve circles in each series, one series, G, resting against or adjacent

to the circle C', at equal distances apart, while the other series, E, extends around the dial ²⁵ inside of the series G, each circle of the latter series, E, extending between and inside of each circle of the adjacent series G. By this means I provide a zigzag series of circles which will present an attractive and ornamental appearance. ³⁰

Having described my invention, I claim—

In a dial, the design which consists of the double series of circles, one series being at the outer periphery of the dial, and the other series extending around the dial inside of the first series, the circles of one series fitting partly between the circles of the other series, as set forth. ³⁵

In testimony that I claim the foregoing as ⁴⁰ my own I have hereto affixed my signature in presence of two witnesses.

JAMES SCOTT.
